F. H. HARDIN

REINFORCING CAR BRACKET

Original Filed Oct. 14, 1924

INVENTOR
FRANK H. HARDIN
By Cornwall, Bidle & James
Attest.

UNITED STATES PATENT OFFICE.

FRANK H. HARDIN, OF BRONXVILLE, NEW YORK.

REENFORCING CAR BRACKET.

Original application filed October 14, 1924, Serial No. 743,600. Divided and this application filed September 27, 1926. Serial No. 137,983.

This invention relates generally to car construction and more particularly to new and useful improvements in reenforcing brackets for car body structures. The present application is a division of an application filed by me October 14, 1924, Serial No. 743,600.

The objects of this invention are to provide a simple bracket for car bodies which is of strong construction and will reenforce the car body against stresses and shocks to which the cars are subjected when in service.

Other objects of the invention are to provide an upwardly projecting reenforcing bracket provided at or near its lower end with a horizontally and inwardly presented member which is adapted to fit into a recess formed in the car underframe and be secured in position therein.

Still other objects of the invention are to provide a single piece casting having an upright member forming reenforcing means for the car body and having a horizontally disposed member extending into a laterally opening recess formed in the car underframe and secured thereto, thereby providing efficient means for tying the car body structure to the underframe.

With these and other objects in view, my invention consists in certain novel features of construction and arrangement of parts, hereinafter more fully described and claimed, and illustrated in the accompanying drawings, in which—

Figure 1 is a top plan view of my improved reenforcing bracket.

Figure 2 is a side elevational view of the same.

Figure 3 is an end elevational view of the same.

Figure 4 is a vertical cross section taken on line 4—4 of Figure 1.

In the construction of railway cars it is desirable to reenforce the car bodies so that they will properly resist shocks and stresses to which cars when in service are subjected. To this end I provide reenforcing brackets having portions for attaching same to the car underframe and provided with suitable attaching surfaces for receiving and having secured thereto the lower ends of car posts, said attaching surfaces being properly

spaced with respect to the car posts of the car body structure.

Referring by numerals to the accompanying drawings, 10 indicates a car underframe having side members 11 provided with outwardly presented horizontally disposed flanges 12 and an end sill 14 provided with an outwardly presented horizontally disposed flange 15. The car underframe 10 is provided in each corner with a rectangular opening 16 which is adapted to receive a rectangular casting 17 formed integral with a reenforcing bracket 18. Casting 17 is provided with a centrally disposed opening 19 and is attached to rails 20 and 21 of said underframe by rivets 22. The outer or attaching faces of casting 17 are provided with pads 23 for engaging the cooperating faces of said rails 20 and 21.

Bracket 18 comprises a side plate 24 having an inwardly presented marginal flange 25 and an end plate 26 having an inwardly presented marginal flange 27. The lower end of plate 24 is provided with a laterally projecting vertically disposed flange 27^a which is reenforced by a horizontally disposed rib or gusset plate 28. This flange 27^a is adapted to have attached thereto by means of rivets 29 the rearwardly presented flange of a corner post 30. End plate 26 is provided at its forward end with the vertically disposed flange 31 which is preferably in the plane with plate 24 and is adapted to have attached to it by means of rivets 32 the web portion of post 30.

This flange 31 is reenforced at its upper end by a horizontally disposed gusset plate 34 which is formed integral with said flange 90 and with the upper end of plate 26. Flange 31 is further reenforced near its lower end by a similar gusset plate 35 and a reenforcing gusset plate 36 is disposed intermediate plates 35 and 34.

A series of vertically disposed reenforcing flanges 37 are formed integral with end plate 26 and project inwardly therefrom and have their lower ends united with the horizontally disposed portion 17 of casting 17. While 100 the upper ends of said flanges unite with the marginal flange 27 of said plate 26, a series of vertically disposed ribs 38 are formed integral with the horizontally presented por-

tion 17^a and the vertically disposed portion 17^b of casting 17 and reenforce the latter.

An end post 39 is secured to plate 26 by means of rivets 40 and a post 41 is secured to

5 the inner end of plate 25 by means of rivets 42. The rear end of plate 26 is recessed as indicated at 44 to provide clearance for the platform portion 45 of underframe 10. Thus the casting 17 of the reinforcing 10 bracket forms a part of the underframe and occupies a position in the recess formed in said underframe with the top of said casting and disposed in substantially the same horizontal plane with the top of said underframe.

15 A reinforcing bracket of my improved construction serves to efficiently tie the car body to the car underframe, provides suitable means for anchoring the lower ends of the post of the car body and reenforce the 20 same against shocks and stresses.

25 While I have shown the preferred form of my invention, it is obvious that various minor changes in the size and construction of my reenforced bracket can be made and substituted for those herein shown and described without departing from the spirit of my invention.

I claim:

1. The combination with a car under- 30 frame of a reinforcing bracket comprising a pair of upright plate members arranged at right angles to each other and provided with laterally extending marginal flanges, a horizontally disposed member formed integral 35 with the lower ends of said plates and engaging said underframe, and a plurality of vertically disposed walls formed integral with said plates and adapted to receive and have secured thereto the car posts of a car wall 40 framing.

2. A one piece reinforcing bracket for cars comprising a pair of plate members arranged at right angles to each other, a rectangular base member arranged inwardly between the lower ends of said plate members and adapted to be secured in a car underframe, a vertically disposed flange extending laterally from one of said plate members and adapted to engage one face of a corner post, 45 a vertically disposed flange extending from the meeting edges of said plate members at right angles to the first flange for engaging a corresponding face of said corner post, and vertically disposed pads arranged on 50 one of said plate members for engaging an intermediate car post.

3. An integral reinforcing bracket for cars comprising a pair of plate members arranged at right angles to each other and 55 provided with inwardly disposed marginal flanges, a rectangular base member arranged inwardly between the lower ends of said plate members and adapted to be secured to a car underframe, vertically disposed and outwardly presented flanges on said plates

for engaging a car corner post, and vertically disposed inwardly presented ribs for reenforcing the end plate and said rectangular base member.

4. The combination of a car underframe 70 having substantially rectangular openings formed in its corners, and a reinforcing corner bracket comprising plate members arranged at right angles to each other and provided with outwardly projecting vertically disposed faces for engaging and having secured thereto the uprights of a car body, and a rectangular base member arranged inwardly between the lower ends of 75 said plate members and occupying the rectangular opening in said car underframe and adapted to be secured therein, and vertically disposed inwardly presented ribs formed on one of said plates and connected to said base member for reenforcing said 80 plate and said base member.

5. The combination of a car underframe having a substantially rectangular opening formed in each corner portion and provided with outwardly presented horizontally disposed flanges at each outer side of said opening, and an integral reinforcing bracket comprising a pair of vertically disposed plate members arranged at right angles to each other and provided with laterally disposed 95 marginal flanges, a substantially rectangular base member formed integral with said plate members and extending inwardly therefrom into the opening in said underframe and adapted to be secured thereto, 100 and vertically disposed and outwardly presented flanges for engaging and having secured thereto the posts of the car body.

6. The combination of a car underframe having a laterally opening recess formed 105 therein and a single piece reinforcing bracket comprising an upright member and a horizontally disposed member extending inwardly from said member into said recess and secured in position therein, said upright 110 member being provided with vertically disposed faces for engaging and having secured thereto the posts of a car body.

7. The combination of a car underframe having a vertically disposed and laterally 115 opening recess formed therein, and a reinforcing bracket comprising a horizontally disposed base member arranged in said recess and secured to said underframe and a vertically disposed plate member formed integral with said base member and provided with inwardly projecting reinforcing flanges and outwardly presented vertically disposed surfaces for receiving and having secured thereto the post of a car body.

8. A reinforcing corner bracket for cars comprising a pair of upright plate members arranged at right angles to each other, a rectangular base member arranged inwardly between the lower ends of said plate mem- 130

bers and adapted to be secured to a car underframe, said plate members being provided at their point of juncture with vertically disposed and outwardly presented surfaces arranged at right angles to each other for engaging the respective faces of a car corner post, and a plurality of verti-

cally disposed faces on one of said plates for receiving and having secured thereto the car posts.

In testimony whereof I hereunto affix my signature this 20th day of September, 1926.

10

FRANK H. HARDIN.
